UNITED STATES PATENT OFFICE

146,014

DESIGN FOR A CLOTHES RACK

Albert J. Berna, Detroit, Mich.

Application February 18, 1946, Serial No. 126,661

Term of patent 14 years

(Cl. D33—8)

To all whom it may concern:

Be it known that I, Albert J. Berna, a citizen of the United States of America, residing at Detroit, in the county of Wayne and State of Michigan, have invented a new, original, and ornamental Design for a Clothes Rack, of which the following is a specification, reference being had therein to the accompanying drawing, forming a part thereof, wherein:

I claim:

The ornamental design for a clothes rack, substantially as shown.

ALBERT J. BERNA.
